FURNITURE CONSTRUCTION

Saul N. Swartz, Cambridge, Mass.

Application March 14, 1946, Serial No. 654,379

5 Claims. (Cl. 5—14)

1

The present invention relates to an article of furniture commonly known as a studio couch which serves both for sleeping purposes and for lounging and is often used in small apartments where a living room must also be used as a bedroom.

In the present invention the so-called studio couch provides a piece of furniture in which one or more cot sections may be stored and concealed so that there is practically no evidence of its character and, further, the stored pieces may be readily removed and set up for use. Two single bed sections may be stored in the studio couch without raising the couch above the normal standard for such articles above the floor.

The stored sections of the couch of the present invention may be contained within the bottom of the studio couch but not supported by it, resting freely on the floor on castors and being drawn out when a closing plate or board has been moved forward and raised. The stored sections of the couch may be retained one in the other but may be removed together or singly, depending on how many sections need to be used for sleeping purposes. Space is also provided for bedding beneath the couch so that the structure is highly economical as regards space and also as regards cost since there are few moving parts or mechanisms to operate, to use the article in any form.

Without further describing the advantages and features of the present invention, the invention will be described in connection with the drawings illustrating an embodiment of the same in which:

Figure 1 shows the invention in perspective with sections broken away illustrating detail elements.

Figure 2 shows one element of the assembly of Figure 1.

Figure 3 shows a further element contained within the structure of Figure 1.

Figure 4 shows a sectional view taken on the line 4—4 of Figure 3 and Figure 5 shows a plan view looking from the top down on the supporting structure with the sofa cushions removed.

In the drawings the couch comprises preferably a wooden base or frame 1 with an upholstered top or cover 2 and serves as a lounge in the ordinary manner. The cover 2 may be made in sections or the top of the couch may be covered or upholstered uniformly all over, over which sectional seats, cushions or pillows are placed. Back pillows or cushions 3 are also used which may be set against the wall if the

couch is used in that position or the couch may have a back support against which the cushions rest. These elements are generally in use and form no special part of the present invention.

5 The frame 1 comprises a back board 4 and side boards 5 with suitable legs or supports 6, 6, etc. at the corners. Cross supports 7, 7, are secured to the back board and front support 8 and in turn these cross supports support both the top 10 cushions which form the seat of the sofa and the slide mechanism by means of which the front door is moved forward. They further provide added strength for the frame. At the front of the couch across the top from leg to leg is a joist or support 8 completing the top of the frame on which the edge of the cushion 2 rests. The cushion or cover 2 also extends downward into the frame and the bottom of it may rest on the cross supports 7. The cushion 2 is made as an individual unit with a frame 60 preferably of wood at its base which rests on the top of the frame 1 and may be readily removed.

Within the space from the cross supports 7 to the floor, the other bed frames are contained 25 with their appurtenances. The bed 10 is contained within the space under the cushion 2. This bed comprises a spring 11 suspended from a frame 12 preferably of metal which in turn is supported at the ends by downwardly extending 20 L-shaped brackets 13 in which the lower portions 14 of the L extend inwardly toward each other. At the ends of the L-shaped brackets are downwardly extending flanges 15 in which castors 16 are supported. At each end of the bed 10, 30 a bar 17 is provided with two ends bent at an angle over the flanges 15 to which they are pivoted in such a way that the bars 17 may be swung downward and serve as supports for the bed. A projecting strip or element 18 may limit the movement of the bar to prevent it from swinging outward, if that is desired. The bars 17 when down should preferably raise the surface of the bed or the mattress 19 to that of the couch cushions.

Within the space defined in part by elements 45 14 and the spring, a further cot frame 20 may be stored. This cot frame folds by means of the jointed links 21 and the pivoted legs 22 in such a manner that the legs fold up under the long span supports 23.

50 Rigidity against lateral sway is obtained by means of the cross piece 24 at either end which comes in contact with the bottom edge of the adjacent L beam across the ends of the frame 20 and prevents motion in a line parallel to the line of axis of the pivots 26 of the legs. The

cot frame 20 may be folded up and slid in the compartment formed above the elements 14 and this space may also hold covers and a mattress if desired. The assembly of the beds or cots 19 and 20 may be pulled out as one unit. Above the unit 10 is sufficient room to store blankets and pillows for both cots 10 and 20.

The front of the couch is covered by means of a hinged and forwardly movable door 39 which is carried by hinges 31, the back half of each of which is supported on a horizontally movable rod or bar 32, 32 and 33, the latter being the central rod by means of which the door is forced forward from the side of the couch by operation of the handle 35 which extends from a horizontal extending slot 36 in one of the boards 5. The rod 33 moves or slides in a bearing 37 and is connected by a pivoted link 28 to the long bar 39 at one end of which is the operating handle 35. The bar 39 is supported in a plurality of wide supports 40 which are secured to the cross boards 7 and which because of their width gives the bar freedom for lateral motion. The end of the bar 39 opposite the operating handle 35 terminates in a connecting member 41 to which one end of link 42 is fastened and, the other end of which is anchored in the back wall 4. The bearing brackets 37 which support rods 32 and 33 are secured to the bottom of the cross bars 7 in the positions as indicated in Figure 5. The links 28 and 42 are freely pivoted so that when the bar 39 is pulled forward and swings slightly laterally, the links 42 and 28 align themselves with the bar 33 and push forward the door 39. The rods 32 simply slide forward with this motion in their bearings. When the door has been pushed forward it may be swung upward and the cots removed from within the compartment under the couch.

In Figure 5 there is shown a full line position of the door 39 when it has been moved forward from its normally closed position. In its closed position the door takes a position under the supporting beam 8 of the frame. The long rod 39 and the handle 35 are shown in the position corresponding to the door when it has been moved away from the frame. The dotted line position of the door corresponds to the door in its closed position under the beam 8.

The beds or cots may be used together, singly or with the couch itself. Sufficient space is provided above the bed or cot 10 to store the necessary blankets and pillows to be used for both beds.

I claim:

1. In combination with a couch a plurality of cot beds adapted to be stored beneath the same comprising one cot bed having supporting L-shaped beams at its ends sustaining the spring of the bed with the bases of the L's extending inwardly of the bed toward one another, a U-shaped bracket having the sides of the U pivoted at the sides of said cot near the ends and adapted to be swung down to form supporting legs for said cot, said L-shaped beams forming a supporting shelf, a second cot having inwardly foldable end legs and adapted when folded to be stored in the shelf of the first cot bed.

2. In a couch having an upholstered top for sleeping purposes, providing a storage space beneath the top for storage of a cot bed, a structure comprising a door hingedly mounted at the front of the couch and covering the front opening between the leg supports and beneath the top of the couch to the floor, a plurality of hinges

each having a half mounted on the inside of the door at the top edge thereof, means supporting the other halves of the hinges for movement normal to the plane of the door when it is in its normal up and down position whereby the door may be moved forward from its normal position and swung upwards on its hinges to open the same.

3. In a couch having an upholstered top for sleeping purposes, providing a storage space beneath the top for storage of a cot bed, a structure comprising a door hingedly mounted at the front of the couch and covering the front opening between the leg supports and beneath the top of the couch to the floor, a plurality of hinges each having a half mounted on the inside of the door at the top edge thereof, means supporting the other halves of the hinges for movement normal to the plane of the door comprising a plurality of parallelly positioned rods to which said other halves of the hinges are attached at one end, means supporting said rods for concomitant axial movement thereof and means operatively attached to one of said rods for advancing said door in a direction perpendicular to its normal position away from said front opening whereby the door may be swung upward on its hinges to open the same.

4. In a couch having an upholstered top for sleeping purposes, providing a storage space beneath the top for storage of a cot bed, a structure comprising a door hingedly mounted at the front of the couch and covering the front opening between the leg supports and beneath the top of the couch to the floor, a plurality of hinges each having a half mounted on the inside of the door at the top edge thereof, means supporting the other halves of the hinges for movement normal to the plane of the door comprising a plurality of parallelly positioned bars to which said other halves of the hinges are attached at one end, means supporting said bars for coaxial movement thereof and means operatively attached to one of said bars comprising three connected link members having one end connected to said bar and the other end fixed to said couch with the middle link member having a long rod extending through one end of the couch and means supporting said link rod for substantial coaxial motion to advance the hinge perpendicular to the normal position of the door whereby the door may be moved forward and swung upward on its hinges to open the same.

5. In combination with a couch having a supporting frame providing substantially elongated rectangular space beneath the same for the enclosure of a cot bed, a plurality of cot beds adapted to be stored beneath the same including one cot bed having supporting L-shaped beams at its ends with the bases of the L's extending inwardly beneath the cot bed towards one another and forming a supporting shelf for a second cot bed, said first cot bed having floor engaging casters attached to the horizontal side of said L-shaped bases and a U-shaped brace pivoted at the ends of said L-shaped beam with the bases of the U extending on the inside around the edge of the horizontal portion of the L-shaped beams and pivoted to be extended below the horizontal portion of the L-shaped beam for raising the cot when the cot has been withdrawn from beneath the couch whereby said cot may be raised to the level of said couch and said second cot bed having inwardly foldable end legs of a size to fit

5

within the supporting shelf formed by said L shaped beams.
